INVENTOR.
Charles R. Birdsey
BY *Langdon, Mow*
ATTORNEY.

UNITED STATES PATENT OFFICE.

CHARLES R. BIRDSEY, OF HINSDALE, ILLINOIS, ASSIGNOR, BY MESNE ASSIGNMENTS, TO UNITED STATES GYPSUM COMPANY, OF CHICAGO, ILLINOIS, A CORPORATION OF ILLINOIS.

LOAD-SUPPORTING BUILDING TILE.

Application filed August 23, 1918. Serial No. 251,115.

To all whom it may concern:

Be it known that I, CHARLES R. BIRDSEY, a citizen of the United States, residing at Hinsdale, in the county of DuPage and State 5 of Illinois, have invented certain new and useful Improvements in Load-Supporting Building Tiles, of which the following is a description.

This invention relates to the construction 10 of tiles for building purposes and more particularly to load supporting building tiles, such as used in roofs.

It is an object of this invention to provide a long span reinforced roof tile of light 15 weight by employing calcined gypsum for its body. It is a further object of this invention to so form the tile as to be economical in the amount of gypsum employed and arrange the reinforcement to afford the 20 greatest strength in proportion to its weight. It is a further object of this invention to so construct the tile that without defacement it may be readily ascertained that the proper reinforcements are embedded in its body.

25 While the preferred forms of this invention are illustrated in the accompanying sheet of drawing, yet minor detail changes may be made without departing from the scope thereof.

30 In the drawing,

Figure 1 is a top plan view of one form of this invention, with parts of the top broken away to show the reinforcing members.

35 Figure 2 is a view in section taken on the line 2—2, Figure 1.

Figure 3 is a view in section taken on the line 3—3, Figure 1.

Figure 4 is a view in section taken on the 40 line 4—4, Figure 1.

Figure 5 is a top plan view of another form of this invention, with part of the top broken away to show a modified form of reinforcement.

45 Figures 6, 7 and 8 are views in section taken on lines 6—6, 7—7, and 8—8, respectively, on Figure 5.

Figure 9 is a view in end elevation.

Figure 10, a similar view, illustrating a 50 modification.

In the constructing of long span gypsum tile, that is a tile of from four to eight feet in length and from one to two feet in width, there are two things that must be 55 considered. The crushing or breaking

strength of gypsum products is very largely increased as the density and weight of the product is increased and the nature of calcined gypsum causes it to expand as it sets, in this latter respect differing from other 60 materials of supposedly similar character which shrink upon setting and the exclusion of the moisture. The density and weight of a gypsum product is limited by the quantity of water or liquid required to cause it to 65 properly pour in the molds, as the ratio of liquid and gypsum is substantially maintained, and a long span roof tile when supported only at its ends must be reinforced to sustain the load and unusual or occasional 70 strains. To reinforce the tile for this purpose it is preferable to employ longitudinal rods positioned in lower portion of the tile below the medial plane and firmly anchored at each end because, owing to its nature gypsum 75 does not have sufficient bond value strength to properly adhere to a reinforcing rod unless it is firmly anchored at its ends. As long span gypsum roof tile is a beam in which the gypsum above the medial plane 80 is the compression member and the reinforcing rods below the medial plane the tension member, the strength of the tile can be regulated by using steel rods and gypsum in proper proportions to withstand the strains 85 set up in the tile by any predetermined load. Tiles of this character as contemplated by this invention are formed in moulds in which the ends of the reinforcing rods forming the tension members are anchored in any 90 preferable manner below the medial plane of the tile and with the rods thus placed, the expanding of the gypsum longitudinally in setting below the medial plane is arrested. The expanding of the tile in the upper portion 95 goes on causing a bowing or crowning of the surface in a longitudinal direction. While it is not necessary to reinforce the slab of gypsum above the medial line, it is preferable to place therein a number of rods crossing each other to form a mat which not only reinforces this portion but the rods arrest the expanding and crowning action of the gypsum above the medial plane.

The preferred form of the tile constructed 105 in accordance with this invention, as illustrated, comprises an upper surface in the form of a flat slab 1 of gypsum having depending edge portions 2 and 3 on the sides and ends of uniform width and depth. Two 110

reinforcing rods 4, forming the tension members, arranged below the medial plane of the tile, one in each depending portion 2 of the longitudinal edges near the bottom, 5 extend continuously from end to end and adjacent each end bent upwardly and then back a substantial distance towards the center parallel to the main body of the rod and near the upper surface above the 10 medial plane as shown in Figures 2 and 6. As stated, the ends of the reinforcing rods 4 should be firmly anchored in the tile, as the tension strains transmitted through the gypsum surrounding the rods is much greater 15 than the bond value of the gypsum to the rods unless so anchored. The bending of the ends of the rods upward and then back for a substantial distance above the medial plane afford the preferred manner for anchoring 20 the ends of the reinforcing rods.

The width of the tile being from twelve to twenty inches, the bowing or crowning in a transverse direction owing to the expansion of the gypsum as it sets is not ordinarily so 25 important to a structure of the kind. It is preferred to prevent this crowning in both longitudinal and transverse directions of the upper surface of the slab 1 above the medial plane by embedding a series of transverse 30 rods 5, extending above the rods 4 and terminating adjacent the sides resting on a series of longitudinal rods 6, extending from end to end, which form a mat within the slab 1 and accomplish both a reinforcement 35 and arrest the uneven expansion of the gypsum in setting. Figures 1 to 4 inclusive illustrate the transverse rods 5 resting on the longitudinal rods 6 and secured to each other, as by spot welding. Figures 5 to 8 40 inclusive illustrate the rods interwoven in which the transverse rods lie substantially in the plane of the bent back portions of the ends of the rods 4 and may be spot welded, if desired.

45 Inspection openings 7 are provided at each end of the tile, as shown in Figure 9, which uncover a portion of the vertically bent end of each reinforcing rod 4, and Figure 10 shows additional inspection openings 8 un- 50 covering the ends of the longitudinal rods 6 forming a part of the mat in the slab 1, and by these openings the rods may be readily seen and their presence assured. This is of great importance as otherwise an inspection 55 of the tile would not in any way disclose the fact that the rods were in place, or had been for any reason omitted which would practically destroy the load carrying power of the tile, and in a tile of this character might 60 result in serious damage and loss.

When these tiles are in position upon a roof it is desirable to close the joints between the various units to prevent the tar or other material that may be placed over

the tile in completing the roof from running 65 down between them. This is prevented by chamfering, notching or otherwise recessing the longitudinal upper edge of the tile, as at 9, to form pockets between the tiles to be filled with a suitable gypsum mortar pre- 70 pared for that purpose.

What I claim is:

1. A load supporting tile having depending edge portions at opposite sides thereof, continuous reinforcing rods in the depending edge portions extending longitudinally thereof below the medial plane of the tile and having end portions extending upwardly and then backwardly horizontally a substantial distance in the main body portion of the tile, and transversely extending reinforcing means embedded in the tile above the medial plane thereof and extending into the edge portions of the tile above said depending edge portions. 85

2. A load supporting building tile having depending edge portions at opposite sides thereof, continuous reinforcing rods in the depending edge portions extending longitudinally thereof below the medial plane of the tile and having end portions extending upwardly and thence backwardly horizontally in the main body portion of the tile above the medial plane thereof, and transverse rods embedded in the tile above 90 the medial plane thereof in the horizontal plane of the backwardly extending end portions of the first mentioned reinforcing rods. 95

3. A building tile having an inspection opening extending from its exterior inwardly 100 thereof, in combination with reinforcing means embedded in the tile and terminating short of the exterior of the tile, said reinforcing means extending to said sight opening. 105

4. A building tile having inspection openings extending from the exterior inwardly at opposite ends thereof, in combination with longitudinally extending reinforcing means embedded in the tile and terminating at its 110 ends short of the exterior of the tile, the end portions of said reinforcing means extending to and disclosed in said sight openings.

5. A building tile having longitudinally extending reinforcing rods embedded therein, said rods having angularly disposed end portions anchored in the tile and said tile being provided with inspection sight openings extending inwardly from the exterior of the tile to the angularly disposed portions 115 of the reinforcing rods. 120

In testimony whereof, I have hereunto signed my name in the presence of two subscribing witnesses.

CHARLES R. BIRDSEY.
